UNITED STATES PATENT OFFICE.

CHESTER H. BURNHAM, OF NORTH ANDOVER, MASSACHUSETTS.

MOUTHPIECE.

1,404,008.

Specification of Letters Patent. Patented Jan. 17, 1922.

Application filed March 29, 1921. Serial No. 456,578.

To all whom it may concern:

Be it known that I, CHESTER H. BURNHAM, a citizen of the United States, residing at North Andover, in the county of Essex 5 and State of Massachusetts, have invented certain new and useful Improvements in a Mouthpiece, of which the following is a specification.

This invention relates to a mouthpiece for 10 horns, bean blowers and the like and has for its principal object to provide means on the mouthpiece for preventing same from being pushed into contact with the throat of the user thereof.

Another object of the invention is to 15 provide means for strengthening the mouthpiece so as to prevent same from becoming easily cracked or otherwise injured.

A still further object of the invention is 20 to generally improve upon mouthpieces of this character by providing a device which will be of extremely simple, durable and inexpensive construction, one which is efficient and reliable in operation and well 25 adapted to the purpose for which it is designed.

With these and numerous other objects in 30 view, the invention resides in certain novel features of construction and arrangement 35 of parts as will be hereinafter fully described and claimed.

In the drawing:—

Figure 1 is a side elevation of the mouthpiece showing same attached to a horn, and 35 Figure 2 is an end elevation thereof.

Referring to the drawing in detail it will be seen that 1 designates a horn of conical construction to which is attached the mouthpiece indicated generally by the numeral 2. This mouthpiece 2 comprises the 40 cylindrical body portion 3 having the conical extension 4 at one end while its other end

is rounded as indicated at 5. A cylindrical bore is provided in the body portion 3 while the extension 4 is provided with a conical 45 bore for receiving the horn 1.

The mouthpiece just described is usually formed of wood and will become easily cracked as is well known and it often happens that the mouthpiece is accidentally 50 forced into engagement with the user's throat as the device is usually used by younger children and in play such accidents frequently happen. I have, therefore, provided means for preventing the mouthpiece 55 from being shoved in engagement with the throat of the user and at the same time bracing the mouthpiece so as to prevent it from becoming easily cracked or otherwise injured. This means preferably consists of 60 the flange 7 which is of the same diameter as the end 8 of the conical extension 4. This flange 7 is suitably fixed to the mouthpiece and is preferably formed of metal or some other strong material and is best situated 65 at the conjunction of the body portion of the conical extension.

Having thus described my invention what I claim as new is:—

A mouthpiece of the class described comprising a cylindrical body portion having one end rounded and a conical extension formed at its other end, and a flange positioned at the juncture of the body portion with its conical extension, said flange being 70 75 of equal diameter with the end of the conical extension.

In testimony whereof I affix my signature in presence of two witnesses.

CHESTER H. BURNHAM.
